UNITED STATES PATENT OFFICE.

CHARLES A. F. DUCORRON, OF LOS ANGELES, CALIFORNIA, ASSIGNOR TO DUCORRON-RICH ENGINEERING COMPANY, OF LOS ANGELES, CALIFORNIA, A PARTNERSHIP CONSISTING OF CHARLES A. F. DUCORRON AND FRANK S. RICH, BOTH OF LOS ANGELES, CALIFORNIA.

BOTTLE HOLDER

Application filed September 1, 1922. Serial No. 585,631.

To all whom it may concern:

Be it known that I, CHARLES A. F. DUCORRON, a citizen of the United States, residing at Los Angeles, in the county of Los Angeles and State of California, have invented new and useful Improvements in Bottle Holders, of which the following is a specification.

This invention relates to an implement for facilitating the carrying and holding of bottles, and more particularly such as common quart and pint milk bottles, and it has for its object to provide a bottle holder or carrier of extreme simplicity, low cost of manufacture and substantial construction. Another object is to provide a bottle holder or carrier having a handle portion from which depends one or more bottle gripping yokes which are of such construction and design that while they may be readily slipped into position to grapple the necks of bottles, they will retain the same firmly in suspended position while the holder is being carried in the hand.

Other objects and advantages will be made manifest in the following specification of an embodiment of the invention illustrated in the accompanying drawings, wherein—

Figure 1 is a perspective of a form of the device having a multiplicity of bottle receiving yokes.

Fig. 2 is a side elevation showing the device as applied to the neck of a bottle which is shown in dotted lines.

Fig. 3 is a plan of a form of the device having a single yoke, a bottle being shown in dotted lines relative thereto.

Fig. 4 is an elevation of a single yoke carrier.

Fig. 5 is an end or edge view of a form of yoke made of a piece of sheet metal.

Fig. 6 is a plan of the form of the type of device shown in Fig. 5.

The bottle holder in its various forms is provided with a substantial semicircular yoke part 2 from the sides of which project tangential bar portions 3, these being arranged in parallelism and bent upwardly as at 4, Fig. 2, from the plane of the yoke or semi-ring part. The ends of the bars 4 are bent upwardly as at 5 and diverge as clearly shown in Fig. 4 so that these bars 5 provide a sufficient throat or opening at the

rear of the carrier to permit the yoke end 55 to be shifted down in front of the bead B of the milk bottle M, and then by shifting the yoke 2 transversely across the neck of the bottle, it is brought in under the bead B which, being of greater diameter than the 60 diameter of the yoke semi-ring, will rest upon the same as the ring is brought upwardly into engagement therewith.

The divergent bars 5 are bent into upwardly extending parallel shank portions 6, 65 and in types of the device made of wire as shown in Figs. 1, 2, 3 and 4, the wire is rolled into eyes 7 and these serve to grip a transverse handle portion or tube 8.

In Fig. 1 there is shown a handle tube 8 70 of sufficient length to receive a plurality, preferably an odd number, of the bottle yokes 2 therefore enabling the application of the device to a plurality of bottles and the carrying of the same at one time in one 75 carrier.

Preferably, the handle portion 8 of the carrier is arranged in approximately the projected axial line of a bottle as indicated in Fig. 2.

A form of the carrier is shown in Figs 5 and 6 as being punched or stamped out of sheet metal thus forming a flat yoke part 2'. The ends of the yoke may be bent upwardly to form shanks 6' which may have a rolled 85 cross handle and connecting part 8'.

The tubular handle of the device provides a receptacle for a simple instrument in the form of a pick having a sharpened penetrating prong 10 and having parallel bars 11 90 merging into an eye or finger ring 12 which is of greater diameter than the diameter of the carrier handle 8. The pick bars 11 are shown in such spaced relation that they may be sprung or compressed inwardly and 95 forced into the guarding tube or handle portion 8. By pulling the pick from the carrier handle, it may then be utilized for removing the ordinary paper caps from milk bottles and may then be readily reinserted 100 in the protecting handle.

Further embodiments, modifications and changes may be resorted to within the spirit of the invention as here claimed.

What is claimed is:

1. A milk bottle holder and carrier consisting of an instrument having a substantially semicircular yoke portion propor-

- tioned to slidably fit the neck of a bottle and to abut against the usual top rim or bead thereof, diametrically opposite ends of the yoke being extended in parallel bars adapted to slide along the neck of a bottle and which have outwardly and upwardly divergent portions to clear the bead of a bottle, said portions being extended into shanks, and a handle connecting the shanks.
- 10 2. A milk bottle holder and carrier consisting of an instrument having a substantially semicircular yoke portion proportioned to slidably fit the neck of a bottle and to abut against the usual top rim or bead thereof, diametrically opposite ends of the yoke being extended in parallel bars adapted to slide along the neck of a bottle and which have outwardly and upwardly divergent portions to clear the bead of a bottle, said portions being extended into shanks, and a handle connecting the shanks, the bars at the end of the yoke being spaced a distance less than the diameter of the bottle bead and serving as stops to limit the outward sliding of the bottle.
- 15 3. A milk bottle holder and carrier consisting of an instrument having a substantially semicircular yoke portion proportioned to slidably fit the neck of a bottle and to abut against the usual top rim or bead thereof, diametrically opposite ends of the yoke being extended in parallel bars adapted to slide along the neck of a bottle and which have outwardly and upwardly divergent portions to clear the bead of a bottle, and a handle.
- 20 4. A milk bottle carrier comprising, in combination, a handle, a pair of shanks connected to the handle, inwardly convergent bar portions at the lower ends of said shanks, substantially parallel bars connected at outer ends by a semicircular yoke, said bars being deflected upwardly from the plane of the yoke to form supporting shoulders when a bottle rests in the yoke.
- 25 5. A milk bottle holder and carrier consisting of an instrument having a substantially semicircular yoke portion proportioned to slidably fit the neck of a bottle and to abut against the usual top rim or bead thereof, diametrically opposite ends of the yoke being extended in parallel bars adapted to slide along the neck of a bottle and which have outwardly and upwardly divergent portions to clear the bead of a bottle, and a handle.

In testimony whereof I have signed my name to this specification.

C. A. F. DUCORRON.
